Primary Examiner — George D. Kirschbaum*Assistant Examiner* — Mary Claire Ramirez*(74) Attorney, Agent, or Firm* — Oblon, McClelland, Maier & Neustadt, L.L.P.**CLAIM**

The ornamental design for an ink cartridge, as shown and described.

DESCRIPTION

FIG. 1 is a front, top, and left side perspective view of an ink cartridge showing the new design;

FIG. 2 is a rear, bottom, and right side perspective view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a rear elevational view thereof;

FIG. 8 is a front elevational view thereof; and,

FIG. 9 is an enlarged rear elevational view thereof.

The broken lines shown in the figures are for the purpose of illustrating portions of the ink cartridge that form no part of the claimed design.
